UNITED STATES PATENT OFFICE.

CHARLES W. SPEAR, OF BRADDYVILLE, IOWA.

IMPROVEMENT IN MARKERS FOR CORN-PLANTERS.

Specification forming part of Letters Patent No. **177,293**, dated May 9, 1876; application filed March 8, 1876.

To whom it may concern:

Be it known that I, CHARLES W. SPEAR, of Braddyville, county of Page, and State of Iowa, have invented certain new and useful Improvements in Markers for Corn-Planters; and I do hereby declare the following to be a full, clear, and exact description of the construction and operation of the same, reference being had to the accompanying drawing, and to the letters of reference marked thereon, in which—

Figure 1 is a top view of my invention in place on a corn-planter. Fig. 2 is a rear elevation of the marker, and Fig. 3 is a detail view or elevation of one of the marker-runners.

The nature of my invention relates to improvements in devices for attaching to corn-planters for the purpose of making a mark in the soil to indicate proper position for the furrow-openers at the next passage of the machine; and the invention consists in the use of an extended bar, carrying markers on each end, and which takes the place of and operates as the double-tree, having the single-trees attached thereto. One end of the marker or both ends may also be hinged, so that it may be turned upward when desired, all as herein-after fully described.

Referring to the parts by letters, letter A represents the forward, and B the rear, part of an ordinary corn-planter, the fore part of which is hinged to the rear part, and carries the usual tongue or draft-pole C. D is a bar extending from the tongue C in each lateral direction a distance beyond each furrow-opener

equal to the distance between the furrow-openers. The bar D is mounted on the tongue C in the usual place for the double-tree, and has the single-trees d attached to its front side. E E' are the drags for making the marks, E being a weight attached, by a chain, e, to the bar D, and E' being a runner-shaped plate, attached directly to the bar D. G is a hinge in one end of the bar D, and permits turning the end of the bar D upward, as shown by dotted lines at Fig. 2. Both ends of the bar D being extended prevents side draft, and the necessity, incident to a single extension, of having to readjust and turn it at the ends of every row. The single-trees being attached to said bar dispenses with the double-tree. The joint G permits turning the end of the bar D upward for the purpose of facilitating passage through gates and other narrow places.

Having thus described my invention, what I claim as new, and desire to secure by Letters Patent, is—

1. The dually-extended bar D, having marking devices on its ends, and pivoted to the draft-pole C, so as to operate as a double-tree, substantially as set forth.

2. In a land-marker, the combination of the draft-pole C with the pivoted bar D, having the single-trees d, and extended hinged ends provided with marking devices, substantially as and for the purpose set forth.

CHARLES W. SPEAR.
